UNITED STATES PATENT OFFICE.

VENCESLAUS F. MIKOLASEK, OF LANKIN, NORTH DAKOTA.

GRAIN-SAVER.

1,110,703.

Specification of Letters Patent. Patented Sept. 15, 1914.

Application filed October 15, 1912. Serial No. 725,846.

To all whom it may concern:

Be it known that I, VENCESLAUS F. MIKOLASEK, a citizen of the United States, residing at Lankin, in the county of Walsh and State of North Dakota, have invented certain new and useful Improvements in Grain-Savers, of which the following is a specification.

This invention is a grain saving attachment for harvesters, and has for its object the provision of a simple and efficient device which may be readily attached to the binder deck of any harvester in position to catch the loose grain, weeds, wild grass, etc., passing over the binder deck and positively feed the same to and into a receptacle supported at one end of the trough. The invention also seeks to provide simple means for supporting the receptacle which may be easily manipulated to permit removal of the receptacle when the same has been filled.

The objects of the invention are attained in a mechanism of the type illustrated in the accompanying drawings, and the invention consists in certain novel features which will be hereinafter first fully described and then more particularly pointed out in the appended claims.

In the drawings: Figure 1 is a plan view 30 of my improved grain saving attachment showing its position relative to the binder deck; Fig. 2 is a longitudinal section of the same; Fig. 3 is an end view, with a part in section, on a larger scale. Fig. 4 is a plan view showing a modification; Fig. 5 is a detail section of a part of the gearing; Fig. 6 is a detail perspective view of the means for attaching the swinging arm shown in Fig. 4.

The binder deck 1 is of the usual or any preferred construction. To the lower edge 40 of the deck, at the front and rear sides thereof, I secure brackets 2 which have down-turned ends to which is secured a trough 3. This trough is preferably formed from a single piece of sheet metal and has its outer wall provided with an outwardly and upwardly inclined deflecting plate 4 at its upper edge so that any loose grain which might 45 tend to pass over the trough and be lost will be caught by said deflecting plate and turned back into the trough, as will be readily understood. At the ends of the trough, I provide cross bars or plates 5 in which is journaled a shaft 6 carrying a spiral or screw 50 conveyer blade 7 and having one end ex-

tended beyond the adjacent end of the trough and equipped with a sprocket wheel 8 which is connected by a sprocket chain 9 with a sprocket wheel on the binder operating shaft or a similar sprocket wheel on the roller at the upper end of the binder deck. The said shaft 6 will thus be rotated so as to impart motion to the spiral or screw conveyer blade and the said blade will consequently be caused to act upon the grain and thereby feed the same toward the discharge end of the trough. At the discharge end of the trough, I secure a supporting arm or bracket 10 and a chute or spout 11, the arm 10 having its lower end formed into a hook 12 which is adapted to engage an opening provided therefor in the side of the box or receptacle 13, and the spout 11 being disposed to discharge directly into the receptacle. At the end of the spout 11, I pivotally secure an attaching hook or finger 14 which is adapted to engage a suitable opening in the side of the receptacle opposite that engaged by the hook 12, and the said hook 14 is extended beyond its pivotal point and equipped with a lateral finger or stop 15 adapted to bear against the under side of the spout and thereby retain the hook in its operative position. The trough is provided 55 with an opening 16 in its bottom at its discharge end directly over the spout so that the grain fed to the discharge end of the trough will pass through the said opening into the receptacle and will not flow past the receptacle onto the ground and be lost.

The receptacle will preferably be extended somewhat laterally from the trough, as indicated most clearly in Fig. 1, so that any loose grain which may happen to roll over the rear edge of the binder deck will be caught by the receptacle.

The sprocket chain 9 passes around a sprocket wheel 17 which may be fitted upon the main shaft or the roller at the upper end of the binder deck, as before stated. The sprocket 17 will be loosely fitted upon the projecting end of the shaft and motion will be imparted to the sprocket from the sprocket wheel 18 on the shaft, to which the sprocket 17 will be rigidly attached by connecting plates or couplings 19 having their ends fitted around the spokes of the respective sprockets and having securing bolts or similar devices 20 inserted through their intermediate portions, as will be readily understood on reference to Fig. 5. By this

simple contrivance, I am enabled to place my grain saving attachment upon any harvester and operatively connect the conveyer with the driving mechanism of the harvester without making any change in said mechanism.

In Fig. 4, I have shown a modification of the device in which the trough is secured to the binder deck, as before, but the receptacle, instead of being hung upon the end of the trough, is carried by a support or arm pivotally mounted below the deck. The trough 3 and the spout 11 may be of the same form as shown in the previously described figures and the conveyer 7 is placed therein, as in the previously described form. Under the deck of the binder, I engage over one of the beams of the frame, a pair of hooks 21 which are connected by a lateral offset or perforated ear 22, and to the said offset or ear I pivotally attach an arm 23 extending rearwardly beyond the binder deck and having its free end equipped with a ring or other circular bag holder 24, as shown clearly in Fig. 4. The ring or bag holder 24 is equipped with a plurality of hooks or spurs 25 over which a bag or other receptacle 26 may be engaged so as to be supported by the holder. To relieve the strain of the supporting arm 23, a hook 27 is secured to the side of the holder 24 and adapted to engage an eye or its equivalent 28 on the end of the trough. With this form of bag holder any ordinary sack or other convenient receptacle may be utilized to catch and hold the grain fed through the trough and when the said receptacle has been filled, it may be removed and another receptacle substituted therefor in a very short period of time. The arm 23 is swung toward the outer or lower end of the spout when the device is in use so that the bag or other receptacle will be supported directly below the mouth of the spout 11, but when it is desired to remove the filled receptacle the hook 27 is disengaged from the eye 28 and the supporting arm is then swung to the position indicated in dotted lines, whereupon the bag may be quickly and easily removed.

The conveyer will be ordinarily so disposed that it will not strike and cut the bundles of grain dropping from the binder deck, but, if so desired, a screen or guard may be placed over the trough so as to prevent the bundles and straw dropping into the trough and clogging the action of the conveyer.

The operation of the device is thought to be evident. The loose grain shaken from the bundles by the operation of the binding mechanism will pass down the binder deck and fall into the trough and be engaged by the spiral conveyer or feeder and thereby forced to the discharge end of the trough, as will be readily understood. This loose grain is now almost invariably lost and the economical desirability of my device is therefore thought to be obvious. The device can be produced at a trifling cost and easily applied to the binder deck of any well-known harvester, and, when repairs are necessary, may be very easily removed. The material caught in the trough will be fed into the receptacle or box 13 until the same has been filled and said box may be then removed and its contents deposited in a suitable sack for subsequent treatment and the box returned to its position upon the trough in a few seconds. When it is desired to remove the receptacle, a slight pressure upon the retaining finger 15 will release the hook 14 and the receptacle may then be lifted from the trough.

What I claim is:

1. In a grain saving device for harvesters, the combination of a harvester deck, a beam beneath the same, a trough connected to the lower side edge of the harvester deck and having a discharge spout at its rear end, a hook engaging over said beam, a rearwardly extending offset on one side of said hook, an arm pivoted to said offset and extending therefrom normally to a point adjacent the discharge spout, a receptacle holder at the rear end of said arm, and means for connecting said holder to the trough.

2. A grain saving attachment for harvesters consisting of a trough provided at its rear end with a downwardly and laterally extending discharge spout, brackets secured to said trough and adapted to be secured to the lower side edge of the harvester deck, and means for supporting a receptacle beneath the discharge spout of the trough with a portion of the receptacle extending laterally from the trough at the rear edge of the harvester deck.

In testimony whereof I affix my signature in presence of two witnesses.

VENCESLAUS F. MIKOLASEK. [L. S.]
